UNITED STATES PATENT OFFICE.

EGERTON RYERSON CASE, OF TORONTO, ONTARIO, CANADA.

ELECTRIC DEVICE FOR TREATING AIR.

1,378,095.

Specification of Letters Patent. Patented May 17, 1921.

Application filed March 22, 1920. Serial No. 367,906.

To all whom it may concern:

Be it known that I, EGERTON RYERSON CASE, a subject of the King of Great Britain, of the city of Toronto, county of York, Province of Ontario, Canada, have invented a certain new and useful Electric Device for Treating Air, of which the following is a specification.

My invention relates to an electric device for treating air, and the principal objects of the invention are to humidify the air in a room, or to treat those suffering from whooping cough or bronchitis, or other bronchial affections, as well as those suffering from throat and lung affections that can be treated in this manner; to supply an insecticide to air in a conservatory containing plants, and to supply a fumigating or deodorizing agent to the air in a room in order to purify the same. Another object of the invention is to expedite the dissemination of the treating agent through the room, and in the following specification several apparatus within my invention will be herein-after particularly described as exemplary means whereby the objects thereof may be carried out, and what I claim as new will be set forth in the claims forming part of this specification.

Figures 1, 2 and 3 are vertical central longitudinal sections through apparatus within my invention showing different embodiments thereof adapted for distributing a liquid and a non-liquid treating agent. Figs. 4 and 5 are vertical cross sections on the lines 4—4, and 5—5, respectively, Fig. 2. Fig. 6 is a vertical central longitudinal section through a modified form of holder for a treating agent, and Fig. 7 is a vertical section on the line 7—7, Fig. 1.

Although in Fig. 1, I show a reflector as associated with one form of my device, it must be clearly understood that I do not confine myself to using a reflector; and when a reflector is used, I do not confine myself to using an apertured reflector, such as is shown in Fig. 1.

The particular form of treating-agent holding-means and the constructions and designs whereby suitable electric connections are had, and the particular construction illustrated for controlling or containing the supply of the treating agent, are not essential to the invention.

Since the quantity of treating agent designed to be held by my device at any one time is relatively quite small, and is preferably located in intimate proximity to the source of heat, it naturally follows that very little time elapses before the treating agent is transformed into the desired state.

The treating agent holding- or containing-means, which also performs the function of a base or support for the resistor in the exemplary disclosures made, may be of metal or of any suitable material well-known in the electrical art, such as porcelain, or fused silica.

C is the base or member supporting the resistor H.

Preferably integrally formed with said base or member C is a flange D provided with a breast E projecting beyond one side thereof to form an annular flange so as to support any suitable screen or guard F, which surrounds the base or member C supporting the resistor. G is a plate faced up against the outer face of the flange D and suitably secured thereto by any suitable fastening means such as nuts and bolts commonly designated I. The plate G is provided with an opening J therethrough, and projecting through said opening J is a tubular member 2 preferably integrally carried by the flange D. 3 is a metal tubular lining for the base or member C, and the tubular member 2, and is designed to contain a non-liquid treating agent 4, which may be of any desired substance such as sulfur, formaldehyde, or spent oxid of iron. Binding posts 5 and nuts, commonly designated 5 may be carried by the plate G to which the ends 6 of the resistor H are connected. The ends 6 pass through suitable holes 7 shown by dotted lines in Fig. 1 formed in the breast E and flange D, and also in the plate G. A certain section of the resistor H is embedded in the longitudinal groove 8 formed in one side of the base or member, and the said groove is afterward closed by any suitable material well-known in the art.

Any means may be employed to introduce the non-liquid treating agent into the metal tubular lining 3. A convenient means for this purpose is as follows: 9 is a cap, which is designed to fit over the flange 10 formed in the outer end of the tubular member 2, and to provide for ease of placing and re-

moval of said cap, a suitable lining 11 is interposed between said cap and said flange 10.

The said cap closes the open end of the 5 said base or member C as well as the tubular lining 3.

The base or member C, and the tubular lining 3 are provided respectively with apertures or holes e and 3' through which escapes 10 the treating agent.

If it is desirous of passing air into the tubular lining 3, this may be done in various ways. For example, ports 12 and 13 may be formed in the lining 3 and base or 15 member C respectively near their intake ends. 14 is a valve or damper mounted to be moved on the flange 10 and between the annular shoulder 15 and the lining 11. This damper is provided with a port 16, which 20 when alined with the ports 12 and 13 permits the passage of air into and through the tubular lining 3.

If desired, the form of device illustrated in Fig. 1 may be provided with any suitable 25 reflector 17 suitably carried by the flange D in any manner well known in the art. For example the reflector 17 may be provided with a flange 18 to fit around the flange D, and the flange 18 may be clamped in place 30 by a split ring 19 having fastening means in the form of ears and a coupling pin commonly designated 20. Formed in the said reflector, if desired, are a plurality of apertures or openings 21 so as to permit currents 35 of air to pass through said reflector and so facilitate the dissemination of the treating agent throughout the room. Since the temperature will be higher on the inner side of the reflector than on the outer side, it follows 40 that currents of air will flow through the apertures or openings 21 into and out of said reflector.

It is well-known in the art that reflectors 45 of different shapes are used to reflect heat waves or rays electrically generated, and these reflected heat waves or rays cause air currents in a room, which also will disseminate the treating agent.

If desired, any suitable pivoting means 50 commonly designated 22, and preferably carried by the plate G may be used to pivot the form of device illustrated in Fig. 1 to a suitable stand or support 23.

The metal lining 3 may be readily re- 55 moved from the base or member C for cleaning purposes.

In Fig. 2, I show substantially the same 60 form of device as is illustrated in Fig. 1, except that the base or member C' does not possess a tubular lining. The resistor H' is coupled to any suitable binding posts 5' and is otherwise suitably associated with said base or member C'. The control of air into 65 and through the base or member C' is controlled by forming a port a in the cap 9', the

port being normally closed by the lining 11'. By loosening the cap 9', the port a may be fully opened to allow passage of air into and through the base or member C'. 4' is the treating agent mounted within the base or 70 member C', and this can be replenished by removing the cap 9' as will be understood.

In Figs. 2 and 3, I show that my device 75 may be employed without the use of a reflector.

The form of disclosure in Fig. 3 shows my device adapted for supplying a liquid treating agent to the air. The base or member C'' preferably integrally forms part of the flange D', though not essentially, and the 80 resistor is carried by the said parts, and suitable electrical connections are had in any suitable manner, as will be understood. Preferably integrally formed with the flange D' is a tubular member 2' which communicates with the interior of the base or member C''. 11'' is a metal lining suitably secured within the tubular member 2' and coupled thereto is the valve casing 24. This valve casing is provided with an inlet 25 whereby 90 fluid is conducted by any suitable means (not shown) from a suitable source of supply (not shown). The valve 26, of a well-known form, controls the supply of fluid through the duct 27 into the base or member C''. 95

The fluid transformed by the heat escapes from the base or member C'' by the aperture or opening 28 preferably located in the position shown in Fig. 3, so that the base or member C'' may contain quite a supply of 100 fluid in the initial stage without the loss of the fluid through the said aperture or opening 28. So soon as the various parts described become fully heated, the fluid escaping from the valve casing 24 will begin to be 105 vaporized.

In the form of base or holder C''' illustrated in Fig. 6, an open trough 29 is provided to receive the treating agent. This form of base or member shows clearly that 110 it is not absolutely necessary to pass the treating agent through the base or member of the device.

While I have described what I consider to be the best embodiments of my invention, I 115 desire it to be understood that the principle may be embodied in many different forms, and I desire not to be limited beyond the requirements of the terms of my claims and the prior art.

What I claim is,

1. A device of the class described and for the purpose set forth including means for carrying a treating agent for air at large, and portable means whereby the same is 125 electrically heated so that one end of said means will have a higher temperature than the other end.

2. A device of the class described and for the purpose set forth including a member 130

- designed to contain a treating agent for air at large, and apertured beyond its receiving end to permit the treating agent to escape therefrom, and means whereby the same is 5 electrically heated.
3. A device of the class described and for the purpose set forth including a member designed to contain a treating agent for air at large, and apertured to permit the treating agent to escape therefrom, and to allow 10 a current of air to pass therethrough, and means whereby the same is electrically heated.
4. A device of the class described and for 15 the purpose set forth including a member designed to contain a treating agent for air at large, and apertured to permit the treating agent to escape therefrom, and to allow a current of air to pass therethrough; closure means for the receiving end of said member, and means whereby said member is electrically heated.
5. A device of the class described and for 20 the purpose set forth including a member designed to contain a treating agent for air at large, and apertured to permit the treating agent to escape therefrom, and to allow a current of air to pass therethrough, a removable apertured lining for said member, and means whereby the same is electrically heated.
6. A device of the class described and for 25 the purpose set forth including an apertured member designed to contain a treating agent for air with which is associated a bore-provided flange which supports a tubular member, which communicates with said first-mentioned member; means whereby said first-mentioned member is electrically heated, 30 and means to control the supply of treating agent to said first-mentioned member, and designed to be carried by said tubular member.
7. A device of the class described and for 35 the purpose set forth including an apertured member designed to contain a treating agent for air with which is associated a bore-provided flange which supports a tubular member, which communicates with said first-mentioned member; means whereby said first-mentioned member is electrically heated; means to control the supply of treating agent 40 to said first-mentioned member, and designed to be carried by said tubular member, and an apertured reflector supported by said flange.
8. A device of the class described and for 45 the purpose set forth including an apertured member designed to contain a treating agent for air with which is associated a bore-provided flange which supports a tubular member, which communicates with said first-mentioned member; means whereby said first-mentioned member is electrically heated; means to control the supply of treating agent 50 to said first-mentioned member, and designed to be carried by said tubular member, and an apertured reflector supported by said flange.
9. As a new article of manufacture, an apertured member made of suitable material that can be heated by electric current, and adapted to contain a treating agent for air; and provided with a port at its intake 55 end to allow air to pass thereto.
10. A device of the class described including electric means to produce heat-waves; means to reflect said heat waves, and adapted to permit a current of air to pass therethrough, and means to supply a treating agent to said reflected heat waves and 60 the current of air passing through said reflecting means.
11. A device of the class described comprising the combination of a suitable reflector; a chambered holder having an outlet and an inlet associated therewith and projecting therethrough; a resistor associated with said holder, and removable closure means for the inlet end of said holder.
12. A device of the class described, and 65 for the purpose set forth, comprising a source of electrical heat, and means heated by said source of heat, and provided with an intake end, and a discharge aperture located in spaced relation to said intake end, 70 and adapted to transform a liquid or non-liquid treating-agent brought into contact therewith into a suitable state for dispersal in the air at large through said discharge aperture.
13. A device of the class described and for 75 the purpose set forth, including a portable member provided with a receiving end, and a discharge aperture located in spaced relation to said receiving end, and adapted to carry a liquid or non-liquid treating-agent for air at large; means whereby the same is electrically heated, and manually operated closure means for the receiving end of said member.
14. A device of the class described and for 80 the purpose set forth, including a chambered member for a treating-agent, having an intake-opening and a discharge aperture spaced apart from said intake-opening; means whereby said chambered member is electrically heated so that the discharge end hereof will be of a higher temperature than the intake end, and closure means for the intake end of said member.

EGERTON RYERSON CASE.
